ROTARY PUMP

Elbert Fowler, Mount Vernon, N. Y., assignor to
Rogers Diesel & Aircraft Corporation, New
York, N. Y.

Application May 17, 1944, Serial No. 535,939

9 Claims. (Cl. 103—138)

This invention relates to rotary pumps of the type having a rotor eccentrically mounted within a housing having a generated bore, said rotor carrying blades arranged in intersecting diametrically extending planes. The blades project outwardly from the rotor into engagement with the walls of the housing so as to carry fluid from an inlet at one side to an outlet at the other side. Due to the eccentric mounting of the rotor with respect to the housing, the blades are alternately extended outwardly from the rotor and withdrawn into the rotor. Heretofore individual blades have been provided in the rotor with springs located behind them to force them outwardly in their slots formed in the rotor. Each blade was thus operated independently of all the other blades. Such a construction is known as the independent blade type, but this type is subject to the objection that difficulties are encountered due to the gumminess of the oil in cold weather starting, and due to the accumulation of sludge which causes sticking of the blades within their slots. Thus, it was frequently found that a blade stuck in its slot and was not projected fully outwardly into engagement with the housing wall, and it was only after the cam surface of the housing was encountered, which operated to force the blade inwardly, that such blade was moved. Hence, it was necessary to employ strong springs sufficient to overcome the gumminess of the oil and the tendency of the blades to stick, but such strength of springs resulted in too much rubbing friction between the rockers at the outer ends of the blades and the wall of the bore, that is, the inside of the housing or the housing liner. Still another objection to these independent blades was inherent in the fact that the short length of blade within the rotor gave a very small spread or bearing surface with which to oppose the torsional effect arising during rotation of the rotor, and this caused rocking movement of the blade with consequent pinching and wearing action.

In an attempt to solve the difficulties inherent in the independent blade type of pump, it has been proposed to employ the type known as through-vanes, wherein a single member extended diametrically across the rotor and carried a blade at each end. This solved certain problems which were inherent in the independent blade type in that a positive force was imparted to both blades whenever either one of them engaged the bore, and since at least one would necessarily be in engagement with the bore, a positive moving or unlocking action was pro-

vided which overcame any tendency to stick, and obviated the necessity of employing springs. Furthermore, the through-vane provided a large spread or bearing surface within the rotor which resulted in less rocking movement than when independent blades were employed, with consequent less tendency to pinch, and less wearing action.

However, in constructing the through-vane type, several difficulties were encountered. It was proposed originally to have the members which extend diametrically inwardly from the opposite blades joined by screws extending through each of the diametric members from one blade and into the cooperating diametrically extending members from the other blade. The screws did not provide sufficient rigidity, and therefore there was a tendency of these diametric members to bend, with consequent pinching effect and wearing of the blades in the slots. These effects were not as great as when independent blades were employed, but they were sufficient to be undesirable. Furthermore, the screws, in spite of any mechanism which could be employed to prevent their becoming slack, nevertheless tended to loosen, and rubbed against the under side of the rockers, thus burring and scuffing up the rockers.

A further disadvantage in this construction resided in the fact that thick blades and connecting members were necessary in order to accommodate screws of sufficient strength to fasten the members together. This disadvantage will be appreciated when it is understood that as the blades discharge the fluid through the discharge port, the camming action withdraws these blades into the rotor. The withdrawal of the blades into the rotor increases the volume of the discharge chamber, and thus reduces the pressure at the discharge end. The thicker the blade, the larger will be the increase in volume, and hence the greater the drop in pressure. This results in fluctuations in the discharge of the fluid with variations in pump pressure, and hence generation of a pulsating discharge. Since a major object of these pumps is to obtain as near to pulsationless discharge as possible, it will be seen that a narrow blade is highly desirable so as not to reduce the pressure substantially when the blade is drawn into the rotor at the discharge end. This precludes the use of screws.

To remedy the objections arising from the construction of through-vanes as described above, it has been proposed to form these through-vanes of unitary members, thus obviating the necessity for employing screws. However, there then arises

the problem of inserting one through-vane within the other through-vane so as to permit the necessary radial movement of each vane relative to the other. For this purpose, it has been proposed to form one of the through-vanes as a frame having a completely enclosed central rectangular opening, and to form the other vane of a modified H-type which is then hooked into this opening, and after being swung into position, is moved axially of the rotor until it assumes its operating position. The disadvantage of this is that it requires extending the slots of at least one of these members through the ends of the rotor and through the end plates where the rotor employs such end plates. This means that the rotor must be sealed at its end faces, which is an operation requiring precision lapping. If there were no openings in the end faces of the rotor, the rotor could be sealed circumferentially adjacent its ends, and this is a relatively cheap grinding operation.

Applicant therefore has for his principal object to provide a rotary pump of the through-vane type which shall be free of all of the objections set forth hereinbefore. Not only does he provide vanes of the through type and thus avoids all of the objections inherent in the type employing a plurality of independent blades, but he provides through-vanes which may be assembled one within the other, allowing for radial movement of each through-vane relative to the other, without necessitating the rotation of one vane in a plane which passes through the axis of the rotor, and therefore without necessitating openings in the rotor ends or the rotor end walls.

Further objects and advantages of this invention will become apparent in the following detailed description thereof.

In the accompanying drawings,

Fig. 1 is a view, partly sectioned vertically, showing a rotary pump constructed according to my invention.

Fig. 2 is a transverse sectional view taken through the pump substantially on the line 2—2 of Fig. 1, and showing the intersecting through-vanes.

Figs. 3—A, 3—B and 3—C are a disassembled view of the through-vanes and one of the rockers, shown in perspective.

Figs. 4—A, 4—B, 4—C, 4—D and 4—E are front elevations showing diagrammatically the steps of assembling one through-vane within the other.

Referring to the drawings, there is shown a rotary pump 18 which comprises the elements of the well known vane type. Such pump includes a hollow casing 11 forming the stator element within which is adapted to rotate the rotor 12 about an axis 13 eccentrically positioned with respect to the axis 14 of the casing 11. The rotor 12 is fixed to a driving shaft 15 which may be driven by any suitable means, as for instance, a belt-and-pulley mechanism 16 which is driven from any suitable source of power such as an electric motor or internal combustion engine. The rotor 12 may be provided with pairs of radial slots 20, 21 and 22, 23 disposed at diametrically opposite points, and within said slots operate through-vanes V and V'. Vane V comprises blades 24 and 25 and connecting members 24' and 25'. Vane V' comprises members 52, 53 and 54 forming at their ends blades 26 and 27. While two sets of diametrically opposed slots have been shown 90° displaced from each other circumferentially of the rotor, it will be understood that more than two such sets of slots may be em-

ployed, such as, for example, three sets displaced 60°.

The casing 11 may be provided with a generated bore 30 of lesser axial length than the interior of the housing, and the blades 24, 25 and 26, 27 may have the same axial length as the bore 30, less clearance. The axial length of rotor 12 being greater than the axial length of the blades 24, 25 and 26, 27, there are therefore formed cylindrical surfaces 32 on said rotor spaced from concentric cylindrical surfaces 33 formed within the hollow casing 11 which is of greater axial length than rotor 12. The space between surfaces 32 and 33 is filled with oil to form oil seals 34. On the inner surface of bore 30 operate rocker members 35 in the outer ends of the vanes.

By reason of the eccentric mounting of the rotor within the bore 30, the blades 24, 25 and 26, 27 will move alternately outwardly and then inwardly in the course of each revolution of the rotor. During the outward movement of each blade there is formed between the blade, the rotor and the bore of the casing, a continuously expanding chamber 45 cooperating with the intake port 48. After the blade has passed the port 48, there will be trapped in chamber 45 the fluid which has been drawn in during the period of expansion of the chamber and its cooperation with the inlet port. During the next half revolution of the 30 rotor, the trapped fluid is discharged through the discharge port 41.

As stated in the introduction hereto, the vanes V and V' are of the through-vane type. That is to say, the blade 24 is not independent of blade 25, but is formed in a single member integrally therewith, and the blade 26 is not independent of the blade 27 but is integral therewith. Furthermore, each of these integral through-vanes is not held together by screws, yet nevertheless, one must pass through the other and each must be relatively movable radially with respect to the other.

For this purpose I form one of the through-vanes, as for instance, the through-vane V as shown in Fig. 3—A in the form of a frame comprising the end members or blades 24, 25, and diametrically extending connecting members 24', 25', all in the form of a rectangle having a rectangular opening 50. The other through-vane member V' must pass through the opening 50 so that it can move freely therethrough diametrically of the rotor, and at the same time permit the through-vane V to move diametrically and freely with respect to member V'. For this purpose I form the through-vane member V' not of a single piece, but of a plurality of members indicated at 52, 53 and 54. Each member, 52 and 53 is in the form of a U-shaped member, the arms of which are designed to face the respective connecting member 24', 25', while the middle member 54 is a spacer or filler member, designed to fill out the space between members 52 and 53 after they have been placed in position. Thus, referring to Fig. 4—A, it will be seen that member 52 can readily be inserted in position within the opening 50 rectilinearly in a diametric direction without rotation in the plane of the rotor axis, and then moved axially to the position shown in Fig. 4—B with its back in engagement with the connecting member 24'. The U-shaped member 53 is then inserted diametrically in the space 58, and then moved axially until its back engages connecting member 25'. There now remains the space between said members into 70 which is inserted the member 54 having a shape

exactly filling the space between backs of the U-shaped members 52 and 53. The ends of the members 52, 53 and 54 are designed to receive a rocker 36 which, when the rotor is positioned within the casing, will engage the bore 30, and thus hold the members in position against movement relative to each other diametrically. Since the total axial length of members 52, 53 and 54 is equal to the axial length, less clearance, of the slot 22 or 23 in which they operate, they will be held against axial displacement. The axial length of the backs of members 52 and 53 plus the axial length of member 54 is equal to the axial length of slot 50, less clearance, and thus will be further held against axial displacement. It will be understood that the axial length of the back of member 52 or the back of member 53, plus the axial length of the arm of U-shaped member 53 or 52, respectively, is less than the axial length of slot 50 as shown in Fig. 4-C. This permits the other U-shaped member to be inserted after one U-shaped member has been positioned.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other equivalent means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In a vane-type rotary pump, a housing having a chamber therein, an inlet passage and a discharge passage communicating with said chamber, a rotor mounted for rotation in said chamber, said rotor having a plurality of sets of axially-disposed slots, one set of slots being angularly displaced relative to the other set of slots circumferentially of the rotor, the slots of each set being positioned diametrically opposite each other, a through-vane extending through each set of slots and having a blade at each end, one of said vanes having an opening within its borders, and the other vane extending through the opening of the first vane and comprising a plurality of separate units, each unit extending in a direction transverse to the axis of rotation of the first vane.

2. In a vane-type rotary pump, a housing having a chamber therein, an inlet passage and a discharge passage communicating with said chamber, a rotor mounted for rotation in said chamber, said rotor having a plurality of sets of axially-disposed slots, one set of slots being angularly displaced relative to the other set of slots circumferentially of the rotor, the slots of each set being positioned diametrically opposite each other, a through-vane extending through each set of slots and having a blade at each end, one of said vanes having an opening within its borders, and the other vane extending through the opening of the first vane and comprising a plurality of separate units arranged contiguously, each unit extending in a direction transverse to the axis of rotation of the first vane the total axial length of the parts of the units which extend through the slots being substantially equal to the axial length of the slots less clearance.

3. In a vane-type rotary pump, a housing hav-

ing a chamber therein, an inlet passage and a discharge passage communicating with said chamber, a rotor mounted for rotation in said chamber, said rotor having a plurality of sets of axially-disposed slots, one set of slots being angularly displaced relative to the other set of slots circumferentially of the rotor, the slots of each set being positioned diametrically opposite each other, a through-vane extending through each set of slots and having a blade at each end, one of said vanes having an opening within its borders, and the other vane extending through the opening of the first vane and comprising a plurality of separate units arranged contiguously, each unit extending in a direction transverse to the axis of rotation of the first vane the total axial length of the parts of the units which extend through the opening in said first vane being substantially equal to the axial length of said opening less clearance.

4. In a vane-type rotary pump, a housing having a chamber therein, an inlet passage and a discharge passage communicating with said chamber, a rotor mounted for rotation in said chamber, said rotor having a plurality of sets of axially-disposed slots, one set of slots being angularly displaced relative to the other set of slots circumferentially of the rotor, the slots of each set being positioned diametrically opposite each other, a through-vane extending through each set of slots and having a blade at each end, one of said vanes having an opening within its borders, and the other vane extending through the opening of the first vane and comprising a plurality of separate units arranged contiguously, each unit extending in a direction transverse to the axis of rotation of the first vane the total axial length of the parts of the units which extend through the slots being substantially equal to the axial length of the slots less clearance, and the total axial length of the parts of the units which extend through the opening in said first vane being substantially equal to the axial length of said opening less clearance.

5. In a vane-type rotary pump, a housing having a chamber therein, an inlet passage and a discharge passage communicating with said chamber, a rotor mounted for rotation in said chamber, said rotor having a plurality of sets of axially-disposed slots, one set of slots being angularly displaced relative to the other set of slots circumferentially of the rotor, the slots of each set being positioned diametrically opposite each other, a through-vane extending through each set of slots and having a blade at each end, one of said vanes having a rectangular opening wholly within its borders to form a framework comprising blade members connected by diametrically extending connecting members, the other vane extending through said opening and comprising a plurality of contiguous units, the outside units being substantially U-shaped, the arms of each U facing the respective connecting member of said framework, the inside unit being adapted to fill the space between the backs of the U-shaped units.

6. In a vane-type rotary pump, a housing having a chamber therein, an inlet passage and a discharge passage communicating with said chamber, a rotor mounted for rotation in said chamber, said rotor having a plurality of sets of axially-disposed slots, one set of slots being angularly displaced relative to the other set of slots circumferentially of the rotor, the slots of each set being positioned diametrically opposite

75 each set being positioned diametrically opposite

each other, a through-vane extending through each set of slots and having a blade at each end, one of said vanes having a rectangular opening wholly within its borders to form a framework comprising blade members connected by diametrically extending connecting members, the other vane extending through said opening and comprising a plurality of contiguous units, the outside units being substantially U-shaped, the arms of each U facing the respective connecting member of said framework, the inside unit being substantially rectangular and adapted to fill the space between the backs of the U-shaped units.

7. In a vane-type rotary pump, a housing having a chamber therein, an inlet passage and a discharge passage communicating with said chamber, a rotor mounted for rotation in said chamber, said rotor having a plurality of sets of axially-disposed slots, one set of slots being angularly displaced relative to the other set of slots circumferentially of the rotor, the slots of each set being positioned diametrically opposite each other, a through-vane extending through each set of slots and having a blade at each end, one of said vanes having a rectangular opening wholly within its borders to form a framework comprising blade members connected by diametrically extending connecting members, the other vane extending through said opening and comprising a plurality of contiguous units, the outside units being substantially U-shaped, the arms of each U facing the respective connecting member of said framework, the inside unit being adapted to fill the space between the backs of the U-shaped units, the total axial length of the parts of said units which extend through the opening being substantially equal to the axial length of said opening less clearance, and the total axial length of the parts of said units which extend through the slots being substantially equal to the axial length of the slots less clearance.

8. In a vane-type rotary pump, a housing hav-

- ing a chamber therein, an inlet passage and a discharge passage communicating with said chamber, a rotor mounted for rotation in said chamber, said rotor having a plurality of sets of axially-disposed slots, one set of slots being angularly displaced relative to the other set of slots circumferentially of the rotor, the slots of each set being positioned diametrically opposite each other, a through-vane extending through each set of slots and having a blade at each end, one of said vanes having a rectangular opening wholly within its borders to form a framework comprising blade members connected by diametrically extending connecting members, the other vane extending through said opening and comprising a plurality of contiguous units, the outside units being substantially U-shaped, the arms of each U facing the respective connecting member of said framework, the inside unit being adapted to fill the space between the backs of the U-shaped units, the axial lengths of the arms of each U-shaped unit plus the axial length of the backs of each unit being less than the axial length of the slots through which they extend.
9. In a vane-type rotary pump, a housing having a chamber therein, an inlet passage and a discharge passage communicating with said chamber, a rotor mounted for rotation in said chamber, said rotor having a plurality of sets of axially-disposed slots, one set of slots being angularly displaced relative to the other set of slots circumferentially of the rotor, the slots of each set being positioned diametrically opposite each other, a through-vane extending through each set of slots and having a blade at each end, one of said vanes having an opening within its borders, and the other vane extending through the opening of the first vane and comprising a plurality of separate units, rockers between each blade and the chamber wall, all of said units engaging a single rocker at each end of the units.

ELBERT FOWLER.
